(57) **CLAIM**

What is claimed is an ornamental design for a corner bracket design, as shown and described herein.

DESCRIPTION

FIG. 1 is a back view of a corner bracket design; FIG. 2 is a front view of the corner bracket design; FIG. 3 is a left view of the corner bracket design; FIG. 4 is a top right front perspective view of the corner bracket design; FIG. 5 is a top view of the corner bracket design; FIG. 6 is a top left front perspective view of the corner bracket design; FIG. 7 is a top right back perspective view of the corner bracket design; FIG. 8 is a right view of the corner bracket design; and, FIG. 9 is a bottom view of the corner bracket design. Broken lines in the drawings are for purposes of illustrating, for example, elements that form no part of the claimed design.
